ABSTRACT

A medicament delivery device for injecting medicament which has a body having a proximal end and a distal end, a needle for injecting medicament and an actuation member which is movable relative to the body. The actuation member is movable from a first position to a second position and movable from the second position to a dispensing position for dispensing medicament from the needle. The second position is proximal of the first position. The medicament delivery device further has a cap which is removably attached to the medicament delivery device. The cap has a portion configured to prevent movement of the actuation member from the first position to the second position when the cap is attached to the medicament delivery device.

MEDICAMENT DELIVERY DEVICE

TECHNICAL FIELD

The present disclosure relates to a medicament delivery device, a method of preparing a medicament delivery device for use and a method of using a medicament delivery device.

BACKGROUND

Medicament delivery devices, such as auto-injectors, are known in the art for dispensing medicament to an injection site of a patient. In some cases, the needle actuator can be depressed accidentally for example before the device is ready and/or in position for use. Depressing the needle actuator accidentally can cause a dose of medicament to be unintentionally dispensed. This can lead to a waste of medicament.

SUMMARY

According to a first aspect of the present disclosure, there is provided a medicament delivery device for injecting medicament, wherein the medicament delivery device comprises a body having a proximal end and a distal end; a needle for injecting medicament; an actuation member which is movable relative to the body, wherein the actuation member is movable from a first position to a second position, wherein the second position is proximal of the first position, and wherein the actuation member is movable from the second position to a dispensing position for dispensing medicament from the needle; and a cap which is removably attached to the medicament delivery device, wherein the cap comprises a portion configured to prevent movement of the actuation member from the first position to the second position when the cap is attached to the medicament delivery device.

The medicament delivery device may comprise a bias configured to bias the actuation member from the first position to the second position.

The actuation member may be proximally movable from the first position to the second position.

The portion of the cap may be configured to prevent proximal movement of the actuation member from the first position to the second position when the cap is attached to the medicament delivery device.

When the actuation member is in the first position then the proximal end of the actuation member may be located distally from the proximal end of the medicament delivery device.

When the actuation member is in the first position then the proximal end of the actuation member may be located distally from the proximal end of the body.

When the actuation member is in the second position then the actuation member may protrude from a part of the medicament delivery device. The part may be the body.

The portion may be a proximally-extending portion.

The actuation member may comprise an axially-extending component which engages the proximally-extending portion when the cap is attached to the medicament delivery device for preventing movement of the actuation member from the first position to the second position.

One of the proximally-extending portion and the axially-extending component may comprise a protrusion and the other of the proximally-extending portion and the axially-extending component may comprise a recess, wherein the protrusion is received in the recess when the cap is attached

2

to the medicament delivery device to prevent movement of the actuation member from the first position to the second position.

At least one of the recess and the protrusion may comprise a ramped surface for allowing the protrusion to disengage the recess when the cap is removed from the medicament delivery device.

The proximally-extending portion may be flexible, and wherein the proximally-extending portion is configured to flex when the cap moves distally and the protrusion disengages the recess.

The medicament delivery device may comprise a lock ring which is configured to rotate the actuation member relative to the body from the second position to a third position. The actuation member may be distally movable from the third position to the dispensing position.

When the cap is attached to the medicament delivery device then the cap may cover the distal end of the body for preventing access to the needle.

The cap may be removably attached to the body.

The device may comprise a dispensing mechanism configured to dispense medicament from the needle, and wherein the actuation member is configured to release the dispensing mechanism when the actuation member is in the dispensing position.

The actuation member may be configured to be rotated relative to the body.

The actuation member may comprise one of a slot and a protrusion, and wherein a second component of the medicament delivery device comprises the other of the slot and the protrusion, wherein the protrusion is located in the slot and wherein the slot has a circumferentially-extending portion configured to rotate the actuation member relative to the second component when the protrusion moves in the circumferentially-extending portion and the actuation member moves from the first position to the second position.

The second component may be the body.

The actuation member may comprise a button configured to be pressed to move the actuation member to the dispensing position.

The medicament delivery device may further comprise a container containing the medicament.

According to another aspect of the present disclosure there is provided a method of preparing a medicament delivery device for use prior to dispensing medicament from the device, the method comprising removing a cap from the medicament delivery device, wherein the cap comprises a portion configured to prevent movement of an actuation member from a first position to a second position when the cap is attached to the medicament delivery device.

The second position is proximal of the first position.

According to another aspect of the present disclosure there is provided a method of using a medicament delivery device, the method comprising removing a cap from the medicament delivery device, wherein the cap comprises a portion configured to prevent movement of an actuation member from a first position to a second position when the cap is attached to the medicament delivery device, and moving the actuation member for dispensing medicament from the medicament delivery device.

The second position is proximal of the first position.

The dispensing position may be distal of the second position.

The needle is for protruding from the distal end of the body for injecting medicament. The needle is for protruding from the distal end of the medicament delivery device for

injecting medicament. The needle may be configured to protrude from the distal end of the body.

The needle may be configured to protrude from the distal end of the body when the actuation member is in the dispensing position. The needle has a distal free end for injecting medicament.

The portion may be a proximally-extending portion.

When the actuation member is in the first position then the actuation member is recessed within the part of the medicament delivery device.

The button may be provided at the proximal end of the medicament delivery device.

Moving the actuation member to the dispensing position may comprise pressing the actuation member.

The actuation member may be configured to release the dispensing mechanism when the actuation member is in the dispensing position. The actuation member may be configured to engage the dispensing mechanism to release the dispensing mechanism when the actuation member is in the dispensing position.

The dispensing mechanism may be configured to cause the needle to move distally from a needle pre-use position to a needle injection position in which the needle protrudes from the distal end of the body when the dispensing mechanism is released.

The dispensing mechanism may comprise a release member and the actuation member may comprise a firing member wherein the firing member is configured to engage the release member to release the dispensing mechanism when the actuation member is in the dispensing position.

The method may further comprise distally moving the actuation member for dispensing medicament from the medicament delivery device.

According to another aspect of the present disclosure there is provided a method of manufacturing or assembling a medicament delivery device, wherein the medicament delivery device is defined in claim 1. Further optional features of the medicament delivery device are described and/or contemplated here.

According to another aspect of the present disclosure there is provided a method of manufacturing or assembling a medicament delivery device, wherein the medicament delivery device has the features of any of the medicament delivery devices described and/or contemplated herein.

BRIEF DESCRIPTION OF THE DRAWINGS

Embodiments will now be described, by way of example only, with reference to the accompanying drawings, in which:

FIG. 1A is a schematic view of a medicament delivery device with a cap attached;

FIG. 1B is a schematic view of the medicament delivery device of FIG. 1A with the cap removed;

FIG. 2A is a schematic view of a medicament delivery device prior to use (i.e. in a pre-use configuration);

FIG. 2B is a schematic view of the device of FIG. 2A with the cap removed;

FIG. 2C is a schematic view of the device of FIG. 2A showing the device placed at an injection site;

FIG. 2D is a schematic view of the device of FIG. 2A with the button having been pressed to release the dispensing mechanism;

FIG. 2E is a schematic view of the device of FIG. 2A with the button having been pressed to release the dispensing mechanism;

FIG. 2F is a schematic view of the device of FIG. 2A showing the needle having retracted within the device after a dose has been delivered;

FIG. 2G is a schematic view of the device of FIG. 2A showing the device removed from the injection site after the needle has retracted within the device after delivery of the medicament;

FIG. 3 is a schematic view of parts of a medicament delivery device according to an embodiment of the present disclosure with the cap attached to the medicament delivery device;

FIG. 4 is a schematic view of parts of a medicament delivery device of FIG. 3 with the cap removed from the medicament delivery device;

FIG. 5A is a plan view of parts of the medicament delivery device of FIG. 3 when the actuation member is in the first position;

FIG. 5B illustrates the position of a protrusion in a slot when the actuation member is in the first position;

FIG. 6A is a plan view of parts of the medicament delivery device of FIG. 3 when the actuation member is in the second position;

FIG. 6B illustrates the position of a protrusion in a slot when the actuation member is in the second position;

FIG. 7A is a plan view of parts of the medicament delivery device of FIG. 3 when the actuation member is in the dispensing position; and

FIG. 7B illustrates the position of a protrusion in a slot when the actuation member is in the dispensing position.

DETAILED DESCRIPTION

A drug delivery device, as described herein, may be configured to inject a medicament into a patient. For example, delivery could be sub-cutaneous, intra-muscular, or intravenous. Such a device could be operated by a patient or care-giver, such as a nurse or physician, and can include various types of safety syringe, pen-injector, or auto-injector. The device can include a cartridge-based system that requires piercing a sealed ampule before use. Volumes of medicament delivered with these various devices can range from about 0.5 ml to about 2 ml. Yet another device can include a large volume device ("LVD") or patch pump, configured to adhere to a patient's skin for a period of time (e.g., about 5, 15, 30, 60, or 120 minutes) to deliver a "large" volume of medicament (typically about 2 ml to about 10 ml).

In combination with a specific medicament, the presently described devices may also be customized in order to operate within required specifications. For example, the device may be customized to inject a medicament within a certain time period (e.g., about 3 to about 20 seconds for auto-injectors, and about 10 minutes to about 60 minutes for an LVD). Other specifications can include a low or minimal level of discomfort, or to certain conditions related to human factors, shelf-life, expiry, biocompatibility, environmental considerations, etc. Such variations can arise due to various factors such as a drug ranging in viscosity from about 3 cP to about 50 cP. Consequently, a drug delivery device will often include a hollow needle ranging from about 25 to about 31 Gauge in size. Common sizes are 27 and 29 Gauge.

The delivery devices described herein can also include one or more automated functions. For example, one or more of needle insertion, medicament injection, and needle retraction can be automated. Energy for one or more automation steps can be provided by one or more energy sources. Energy sources can include, for example, mechanical, pneumatic, chemical, or electrical energy. For example, mechani-

cal energy sources can include springs, levers, elastomers, or other mechanical mechanisms to store or release energy. One or more energy sources can be combined into a single device. Devices can further include gears, valves, or other mechanisms to convert energy into movement of one or more components of a device.

The one or more automated functions of an auto-injector may each be activated via an activation mechanism. Such an activation mechanism can include one or more of a button, a lever, a needle sleeve, or other activation component. Activation of an automated function may be a one-step or multi-step process. That is, a user may need to activate one or more activation components in order to cause the automated function. For example, in a one-step process, a user may depress a needle sleeve against their body in order to cause injection of a medicament. Other devices may require a multi-step activation of an automated function. For example, a user may be required to depress a button and retract a needle shield in order to cause injection.

In addition, activation of one automated function may activate one or more subsequent automated functions, thereby forming an activation sequence. For example, activation of a first automated function may activate at least two of needle insertion, medicament injection, and needle retraction. Some devices may also require a specific sequence of steps to cause the one or more automated functions to occur. Other devices may operate with a sequence of independent steps.

Some delivery devices can include one or more functions of a safety syringe, pen-injector, or auto-injector. For example, a delivery device could include a mechanical energy source configured to automatically inject a medicament (as typically found in an auto-injector) and a dose setting mechanism (as typically found in a pen-injector).

According to some embodiments of the present disclosure, an exemplary drug delivery device 10 is shown in FIGS. 1A & 1B. The device 10, as described above, is configured to inject a medicament into a patient's body. The device 10 includes a housing 11 which typically contains a reservoir containing the medicament to be injected (e.g., a syringe) and the components required to facilitate one or more steps of the delivery process. The device 10 can also include a cap assembly 12 that can be detachably mounted to the housing 11. A user typically removes the cap assembly 12 from the housing 11 before the device 10 is operated.

As shown, the housing 11 is substantially cylindrical and has a substantially constant diameter along the longitudinal axis X. The housing 11 has a distal region 20 and a proximal region 21. The term "distal" refers to a location that is relatively closer to a site of injection, and the term "proximal" refers to a location that is relatively further away from the injection site.

The device 10 can also include a needle sleeve 13 coupled to the housing 11 to permit movement of the sleeve 13 relative to the housing 11. For example, the sleeve 13 can move in a longitudinal direction parallel to longitudinal axis X. Specifically, movement of the sleeve 13 in a proximal direction can permit a needle 17 to extend from distal region 20 of the housing 11.

Insertion of the needle 17 can occur via several mechanisms. For example, the needle 17 may be fixedly located relative to the housing 11 and initially be located within an extended needle sleeve 13. Proximal movement of the sleeve 13 by placing a distal end of the sleeve 13 against a patient's body and moving the housing 11 in a distal direction will uncover the distal end of the needle 17. Such relative movement allows the distal end of the needle 17 to

extend into the patient's body. Such insertion is termed "manual" insertion as the needle 17 is manually inserted via the patient's manual movement of the housing 11 relative to the sleeve 13.

Another form of insertion is "automated," whereby the needle 17 moves relative to the housing 11. Such insertion can be triggered by movement of the sleeve 13 or by another form of activation, such as, for example, a button 22. As shown in FIGS. 1A & 1B, the button 22 is located at a proximal end of the housing 11. However, in other embodiments, the button 22 could be located on a side of the housing 11.

Other manual or automated features can include drug injection or needle retraction, or both. Injection is the process by which a bung or piston 23 is moved from a proximal location within a syringe (not shown) to a more distal location within the syringe in order to force a medicament from the syringe through the needle 17. In some embodiments, a drive spring (not shown) is under compression before the device 10 is activated. A proximal end of the drive spring can be fixed within the proximal region 21 of the housing 11, and a distal end of the drive spring can be configured to apply a compressive force to a proximal surface of the piston 23. Following activation, at least part of the energy stored in the drive spring can be applied to the proximal surface of the piston 23. This compressive force can act on the piston 23 to move it in a distal direction. Such distal movement acts to compress the liquid medicament within the syringe, forcing it out of the needle 17.

Following injection, the needle 17 can be retracted within the sleeve 13 or the housing 11. Retraction can occur when the sleeve 13 moves distally as a user removes the device 10 from a patient's body. This can occur as the needle 17 remains fixedly located relative to the housing 11. Once a distal end of the sleeve 13 has moved past a distal end of the needle 17, and the needle 17 is covered, the sleeve 13 can be locked. Such locking can include locking any proximal movement of the sleeve 13 relative to the housing 11.

Another form of needle retraction can occur if the needle 17 is moved relative to the housing 11. Such movement can occur if the syringe within the housing 11 is moved in a proximal direction relative to the housing 11. This proximal movement can be achieved by using a retraction spring (not shown), located in the distal region 20. A compressed retraction spring, when activated, can supply sufficient force to the syringe to move it in a proximal direction. Following sufficient retraction, any relative movement between the needle 17 and the housing 11 can be locked with a locking mechanism. In addition, the button 22 or other components of the device 10 can be locked as required.

FIGS. 2A to 2G show the sequential steps of operating a medicament delivery device 200. The medicament delivery device 200 is an autoinjector.

The device 200 comprises a body 201, a syringe 250 having a needle 217 and an axially moveable plunger 223 for dispensing medicament from the syringe 250. The device comprises a cap 254 which is removably attached to the body 201 and covers a distal end 202 of the body 201 for preventing access to the needle 217. The device has a needle shield 266 that covers the needle 217 before use. The needle shield 266 is attached to the cap 254.

The medicament delivery device 200 has a dispensing mechanism 229. The medicament delivery device 200 has an actuation member 227 which is configured to release the dispensing mechanism 229. The actuation member 227 is configured to engage the dispensing mechanism 229 to release the dispensing mechanism 229.

The dispensing mechanism 229 is configured to cause the needle 217 to move distally from a needle pre-use position, in which the needle 217 is recessed within the body 201, to an injection position in which the needle 217 protrudes from the distal end 202 of the body 201 when the dispensing mechanism 229 is released.

The dispensing mechanism 229 is configured to dispense the medicament from the needle 217 when the needle 217 is in the injection position.

As shown in FIGS. 2B-2C, in order to deliver a dose of medicament to an injection site, the cap 254 is removed (FIG. 2B) and the device is placed at an injection site 232 (FIG. 2C).

The actuation member 227 comprises a button 228 and is prevented from being depressed by a stop 258. The stop is provided on the spring guide 240, for example.

The device has a locking member 208 in the form of a lock ring 216 which is rotatable by a user about a longitudinal axis of the device. The actuation member 227 is keyed to the lock ring 216 so that the actuation member 227 rotates with the lock ring 216. The lock ring 216 is rotatable from a pre-use position, in which distal movement of the button 228 is prevented, to a use position in which distal movement of the button 228 is permitted.

When the lock ring 216 is in the pre-use position then the stop 258 engages the button 228 to prevent the button 228 from being depressed.

In order to allow the button 228 to be depressed, the lock ring 216 is rotated about the longitudinal axis of the device from the pre-use position to the use position. The rotation of the lock ring 216 also rotates the actuation member 227 to a position in which the stop 258 no longer prevents the button 228 from being depressed as shown, for example, in FIG. 2C.

Turning now to FIG. 2D, the user then presses the button 228 to release the dispensing mechanism 229 for dispensing medicament from the device. The dispensing mechanism 229 has a plunger 223 and a bias in the form of a compression spring 260. The plunger 223 is biased distally by the spring 260.

The dispensing mechanism 229 is at least partially housed within the spring guide 240. The plunger 223 has a release member which has proximally-extending clips 264. The spring 260 is retained in the compressed position by virtue of the clips 264 which protrude through a proximal opening 265 in the spring guide 240. The clips 264 engage the spring guide 240 for maintaining the plunger 223 in a proximal position.

The actuation member 227 has a firing member comprising a pair of protrusions 242 which engage with the clips 264 when the button 228 is depressed to flex the clips 264 radially inwardly thereby allowing the clips 264 to move distally through the proximal opening 265 to release the spring 260.

When the dispensing mechanism 229 is released, then the syringe 250 is released for distal axial movement towards the injection site 232 such that the needle 217 moves from the needle pre-use retracted position to an exposed (or "uncovered" or "injection") position for delivering medicament to the injection site 232 under the biasing force of the compression spring 260.

Depressing the button 228 releases the plunger 223 which, biased by the bias 260, moves along the syringe 250 towards the distal end of the device 200 to force medicament within the syringe 250 through the needle 217, thereby delivering a dose of medicament as shown, for example in FIG. 2E.

As shown in FIG. 2F, once the dose of medicament has been delivered, a medicament container bias 262, embodied by a further spring 262, then causes the needle 217 to move axially back to the retracted position, away from the injection site 232 in a proximal direction. The plunger 223 flexes a clip (not shown) on a first collar 267 which allows the first collar 267 to rotate relative to the body 201 and relative to a second collar 268. The first collar 267 rotates from a first position in which the second collar 268 is axially coupled to the first collar 267, into a second position in which the second collar 268 is free to move axially relative to the first collar 267. For example, the second collar 268 may comprise a radially protruding coupling element configured to be received in or engage with a corresponding receiving portion of the first collar 267, such that rotating the first collar 267 from the first position into the second position causes the coupling element to be moved out from the receiving portion, to allow the second collar 268 to move axially relative to the first collar 267. Axial movement of the second collar 268 permits the needle 217 to be retracted.

As shown in FIG. 2G, the device 200 is then removed from the injection site 232, for disposal.

FIG. 3 is a schematic view of parts of a medicament delivery device 300 according to an embodiment of the present disclosure. In FIG. 3 the cap 354 is attached to the medicament delivery device 300. FIG. 4 is a schematic view of parts of a medicament delivery device of FIG. 3 with the cap 354 removed from the medicament delivery device 300.

The medicament delivery device 300 has a body 301 having a proximal end 303 and a distal end 302. The medicament delivery device 300 has a needle 217 for injecting medicament. The device 300 has an actuation member 327 which is movable relative to the body 301.

The needle 217 is for protruding from the distal end of the medicament delivery device for injecting medicament. The needle 217 is for protruding from the distal end 302 of the body for injecting medicament. The needle 217 is configured to protrude from the distal end of the body 301 when the actuation member is in the dispensing position. The needle 217 has a distal free end for injecting medicament.

The actuation member 327 is proximally movable from a first position to a second position. FIG. 3 shows the actuation member in an example first position. FIG. 4 shows the actuation member 327 in an example second position. The actuation member 327 is distally movable from the second position to a dispensing position for dispensing medicament from the needle 217.

When the actuation member 327 is in the first position then the proximal end 329 of the actuation member is located distally from the proximal end 330 of the medicament delivery device. In another embodiment (not shown) when the actuation member 327 is in the first position then the proximal end 329 of the actuation member is flush with the proximal end 330 of the medicament delivery device.

When the actuation member 327 is in the second position then the actuation member 327 protrudes from a part of the medicament delivery device 300. The actuation member 327 protrudes from the proximal end of the part. When the actuation member 327 is in the first position then the actuation member is recessed within the part of the medicament delivery device or flush with the proximal end of the part of the medicament delivery device. In the example shown in FIGS. 3 and 4, the part is the lock ring 216. The actuation member 327 protrudes proximally from the lock ring 216 when the actuation member 327 is in the second position. The actuation member 327 is recessed within the

lock ring 216 or flush with the proximal end of the lock ring when the actuation member 327 is in the first position.

However, in another embodiment the lock ring 216 is not present. The part may be the body 301 and the actuation member 327 protrudes proximally from the body 301 when the actuation member 327 is in the second position. The actuation member 327 is recessed within the body 301 or flush with the proximal end of the body when the actuation member 327 is in the first position.

When the actuation member 327 is in the second position then the actuation member 327 forms the proximal-most extent of the device 300.

The medicament delivery device 300 has a bias 360 configured to bias the actuation member 327 from the first position to the second position. The bias 360 is a spring, for example. When the cap 354 is removed from the medicament delivery device 300 then the bias 360 is configured to move the actuation member from the first position to the second position.

The cap 354 is removably attached to the body 301. The cap 354 has a portion 318 which is configured to prevent proximal movement of the actuation member 327 from the first position to the second position when the cap 354 is attached to the medicament delivery device. The cap 354 may have one or more apertures.

The portion 318 is a proximally-extending portion. The proximally-extending portion may extend into the body 301 when the cap 354 is attached to the body 301. The actuation member 327 has an axially-extending component 319 which engages the proximally-extending portion 318 when the cap 354 is attached to the medicament delivery device for preventing proximal movement of the actuation member 327 from the first position to the second position.

The proximally-extending portion 318 has a protrusion 331 and the axially-extending component 319 has a recess 332. The protrusion 331 is received in the recess 332 when the cap 354 is attached to the medicament delivery device to prevent proximal movement of the actuation member 327 from the first position to the second position.

The protrusion 331 has a ramped surface 333 for allowing the protrusion 331 to disengage the recess 332 when the cap 354 is removed from the medicament delivery device. The ramped surface 333 is a planar surface at an acute angle to the longitudinal axis 334 of the medicament delivery device. Alternatively or additionally the ramped surface 333 may comprise a curved surface. In another embodiment, the recess additionally or alternatively comprises the ramped surface 333.

The protrusion engages a proximal-facing surface 340 of the recess 332.

The proximally-extending portion 318 is flexible. The proximally-extending portion 318 is configured to flex when the cap 354 moves distally and the protrusion 331 disengages the recess 332.

In another embodiment, the axially-extending component 319 has the protrusion 331 and the proximally-extending portion 318 has the recess 332. The protrusion 331 is received in the recess 332 when the cap 354 is attached to the medicament delivery device to prevent proximal movement of the actuation member 327 from the first position to the second position. In this embodiment, the axially-extending component may be 319 flexible. The axially-extending component 319 is configured to flex when the cap 354 moves distally and the protrusion 331 disengages the recess 332.

The recess 332 may be an aperture in the axially-extending component 319 or the proximally-extending portion 318.

In another embodiment, the recess may be a portion of reduced thickness of the axially-extending component 319 or the proximally-extending portion 318.

The proximally-extending portion 318 is a first axially-extending arm. The axially-extending component 319 is a second axially-extending arm. The first axially-extending arm 318 and the second axially-extending arm 319 form a pair of arms which interact to prevent proximal movement of the actuation member 327 from the first position to the second position when the cap 354 is attached to the body. The medicament delivery device 300 has two pairs of arms wherein each pair of arms has the same features as described and/or contemplated herein in relation to the first axially-extending arm and the second axially-extending arm. In another embodiment, just a single pair of arms or more than two pairs of arms may be present in the device wherein the or each pair of arms has the same features as described herein in relation to the proximally-extending portion 318 and the axially-extending component 319. Each of the pairs of arms may be spaced around the circumference of the device, for example the pair of arms may be equally spaced around the circumference.

In another embodiment, the axially-extending component 319 and/or the proximally-extending portion 318 comprises a sleeve, for example a circular sleeve. The or each recess 332 may be provided in the sleeve.

In another embodiment the cap 354 may be removably attached to another component of the medicament delivery device.

The cap 354 is configured to be pulled off the medicament delivery device 300. In another embodiment, the cap 354 is configured to be twisted off the medicament delivery device. For example, the protrusion 331 and recess 332 may form a bayonet mount.

The medicament delivery device 300 has a dispensing mechanism 229 configured to dispense medicament from the needle 217. The actuation member 327 is configured to release the dispensing mechanism 229 when the actuation member 327 is in the dispensing position.

The dispensing mechanism 229 has a release member which comprises a pair of clips 264. The actuation member has a firing member which comprises a pair of protrusions 242 which are configured to engage the pair of clips 264 to release the dispensing mechanism 229 when the actuation member 327 is in the dispensing position.

When the actuation member 327 is in the first position then the pair of clips 264 and the pair of protrusions 242 are circumferentially offset relative to each other about the longitudinal axis. This can be seen in FIG. 3 and FIG. 5A.

When the actuation member 327 is in the second position then the pair of clips 264 and the pair of protrusions 242 are circumferentially aligned relative to each other about the longitudinal axis. This can be seen in FIG. 4 and FIG. 6A.

When the actuation member 327 is in the dispensing position then the pair of clips 264 and the pair of protrusions 242 are circumferentially aligned relative to each other about the longitudinal axis. This can be seen in FIG. 7A.

The actuation member 327 has a protrusion 335. A second component of the medicament delivery device, for example the body 301, has a slot 336. The protrusion 335 is located in the slot 336. The slot 336 has a circumferentially-extending portion 337 which is configured to rotate the actuation member 327 relative to the second component when protrusion 335 moves in the circumferentially-extending portion 337 and the actuation member 327 moves from the first position to the second position.

11

FIG. 5B shows the position of the protrusion 335 in the slot 336 when the actuation member 327 is in the first position. FIG. 6B shows the position of the protrusion 335 in the slot 336 when the actuation member 327 is in the second position. FIG. 7B shows the position of the protrusion 335 in the slot 336 when the actuation member 327 is in the dispensing position.

The slot 336 has a first axially-extending portion 338 which allows the actuation member 327 to move axially relative to the second component when the actuation member 327 moves from the first position to the second position. The slot 336 has a second axially-extending portion 339 which allows the actuation member 327 to move axially relative to the second component when the actuation member 327 moves from the second position to the dispensing position.

In another embodiment the second component may be another component of the medicament delivery device, for example the spring guide 240.

In another embodiment the actuation member 327 has the slot 336 and the second component has the protrusion 335.

The slot 336 and the protrusion 335 allow the actuation member 327 to be rotated into position for engaging the clips 264.

In another embodiment, the actuation member 327 is not rotated relative to the second component, for example the body 301, when the actuation member 327 moves from the first position to the second position. The slot 336 and the protrusion 335 may not be present in the medicament delivery device.

In another embodiment, the lock ring 216 is configured to rotate the actuation member 327 relative to the body 301 from the second position to a third position. The actuation member 327 is distally movable from the third position to the dispensing position.

In another embodiment, the lock ring 216, the slot 336 and the protrusion 335 are present in the device and are all operable to rotate the actuation member 327 relative to the body 301. The circumferentially-extending portion 337 of the slot 336 is configured to rotate the actuation member 327 relative to the second component when the protrusion 335 moves in the circumferentially-extending portion 337 and the actuation member 327 moves from the first position to the second position. The lock ring 216 is then rotated to rotate the actuation member 327 from the second position to a third position. The actuation member 327 is then distally movable from the third position to the dispensing position.

When the actuation member 327 is in the second position then distal movement of the actuation member 327 is prevented, for example by the stop 258 as described and/or contemplated in relation to FIGS. 2A to 2G above.

The actuation member 327 has a button 338 which is configured to be pressed to move the actuation member 327 to the dispensing position. The axially-extending component 319 may be integrally formed with the button or be a separate component which is fixedly joined to the button 338.

The medicament delivery devices described herein may have some or all of the features as described in relation to the medicament delivery device 200.

The dispensing mechanism 229 may have the some or all of the features as described and/or contemplated in relation to FIGS. 2A to 2G.

In another embodiment, the dispensing mechanism may have alternative or additional features to those described and/or contemplated in relation to FIGS. 2A to 2G. The

12

dispensing mechanism may have features as described and/or contemplated herein, for example in relation to FIGS. 1A and 1B.

The dispensing mechanism provides one or more automated functions. For example, one or more of needle insertion, medicament injection, and needle retraction can be automated. Energy for one or more automation steps can be provided by one or more energy sources. Energy sources can include, for example, mechanical, pneumatic, chemical, or electrical energy. For example, mechanical energy sources can include springs, levers, elastomers, or other mechanical mechanisms to store or release energy. One or more energy sources can be combined into a single device. Devices can further include gears, valves, or other mechanisms to convert energy into movement of one or more components of a device.

The one or more automated functions may each be activated via an activation mechanism. Such an activation mechanism can include one or more of a button, a lever, a needle sleeve, or other activation component. Activation of an automated function may be a one-step or multi-step process. That is, a user may need to activate one or more activation components in order to cause the automated function. For example, in a one-step process, a user may depress a needle sleeve against their body in order to cause injection of a medicament. Other devices may require a multi-step activation of an automated function. For example, a user may be required to depress a button and retract a needle shield in order to cause injection.

In addition, activation of one automated function may activate one or more subsequent automated functions, thereby forming an activation sequence. For example, activation of a first automated function may activate at least two of needle insertion, medicament injection, and needle retraction. Some devices may also require a specific sequence of steps to cause the one or more automated functions to occur. Other devices may operate with a sequence of independent steps.

Some delivery devices can include one or more functions of a safety syringe, pen-injector, or auto-injector. For example, a delivery device could include a mechanical energy source configured to automatically inject a medicament (as typically found in an auto-injector) and a dose setting mechanism (as typically found in a pen-injector).

The medicament delivery device can include various types of safety syringe, pen-injector, or auto-injector. The device can include a cartridge-based system that requires piercing a sealed ampule before use.

Distal movement of the actuation member may cause automatic dispensing of the medicament from the device and/or distal movement of the actuation member may cause the distal movement of the needle from a needle pre-use position to a needle injection position. The dispensing mechanism may be configured to dispense medicament from the needle when the dispensing mechanism is released.

In the needle pre-use position the needle may be flush with the distal end of the body or the needle may be recessed within the body. In another embodiment the needle may be fixed in position relative to the body.

In another device, different features may be provided to prevent the actuation member from moving distally. For example, the stop may be provided on another component of the medicament delivery device. In another device a lock ring 216 is not present.

In use, the cap 354 is removed from the medicament delivery device 300, for example by a user. In some embodiments, the lock ring 216 (if present) is then rotated from the

pre-use position to the use position. The button 338 is then pressed, for example by the user, when the medicament delivery device 300 is held against an injection site 232 to dispense the medicament via the needle 217.

The portion 318 prevents the medicament from being accidentally dispensed from the needle 217 before the cap 354 has been removed from the device. When the cap 354 is attached to the medicament delivery device 300, the actuation member 327 is in a first or inoperable position. The actuation member 327 moves proximally and is presented for use when the cap 354 is removed from the device.

In another embodiment, it is possible that the actuation member 327 could initially move distally from the first position before it moves proximally to the second position when the cap is removed from the medicament delivery device. The second position is still proximal of the first position.

A method of using the medicament delivery device 300 comprises removing the cap 354 from the medicament delivery device. The medicament delivery device may have any of the features described and/or contemplated herein. Optionally, the method comprises rotating the lock ring from a pre-use position to a use position. The method may further comprise moving the actuation member to the dispensing position. Moving the actuation member to the dispensing position may comprise a user pressing the button 338.

The terms "drug" or "medicament" are used synonymously herein and describe a pharmaceutical formulation containing one or more active pharmaceutical ingredients or pharmaceutically acceptable salts or solvates thereof, and optionally a pharmaceutically acceptable carrier. An active pharmaceutical ingredient ("API"), in the broadest terms, is a chemical structure that has a biological effect on humans or animals. In pharmacology, a drug or medicament is used in the treatment, cure, prevention, or diagnosis of disease or used to otherwise enhance physical or mental well-being. A drug or medicament may be used for a limited duration, or on a regular basis for chronic disorders.

As described below, a drug or medicament can include at least one API, or combinations thereof, in various types of formulations, for the treatment of one or more diseases. Examples of API may include small molecules having a molecular weight of 500 Da or less; polypeptides, peptides and proteins (e.g., hormones, growth factors, antibodies, antibody fragments, and enzymes); carbohydrates and polysaccharides; and nucleic acids, double or single stranded DNA (including naked and cDNA), RNA, antisense nucleic acids such as antisense DNA and RNA, small interfering RNA (siRNA), ribozymes, genes, and oligonucleotides. Nucleic acids may be incorporated into molecular delivery systems such as vectors, plasmids, or liposomes. Mixtures of one or more drugs are also contemplated.

The drug or medicament may be contained in a primary package or "drug container" adapted for use with a drug delivery device. The drug container may be, e.g., a cartridge, syringe, reservoir, or other solid or flexible vessel configured to provide a suitable chamber for storage (e.g., short- or long-term storage) of one or more drugs. For example, in some instances, the chamber may be designed to store a drug for at least one day (e.g., 1 to at least 30 days). In some instances, the chamber may be designed to store a drug for about 1 month to about 2 years. Storage may occur at room temperature (e.g., about 20° C.), or refrigerated temperatures (e.g., from about -4° C. to about 4° C.). In some instances, the drug container may be or may include a dual-chamber cartridge configured to store two or more components of the pharmaceutical formulation to-be-administered (e.g., an API

and a diluent, or two different drugs) separately, one in each chamber. In such instances, the two chambers of the dual-chamber cartridge may be configured to allow mixing between the two or more components prior to and/or during dispensing into the human or animal body. For example, the two chambers may be configured such that they are in fluid communication with each other (e.g., by way of a conduit between the two chambers) and allow mixing of the two components when desired by a user prior to dispensing.

10 Alternatively or in addition, the two chambers may be configured to allow mixing as the components are being dispensed into the human or animal body.

The drugs or medicaments contained in the drug delivery devices as described herein can be used for the treatment and/or prophylaxis of many different types of medical disorders. Examples of disorders include, e.g., diabetes mellitus or complications associated with diabetes mellitus such as diabetic retinopathy, thromboembolism disorders such as deep vein or pulmonary thromboembolism. Further examples of disorders are acute coronary syndrome (ACS), angina, myocardial infarction, cancer, macular degeneration, inflammation, hay fever, atherosclerosis and/or rheumatoid arthritis. Examples of APIs and drugs are those as described in handbooks such as Rote Liste 2014, for example, without limitation, main groups 12 (anti-diabetic drugs) or 86 (oncology drugs), and Merck Index, 15th edition.

Examples of APIs for the treatment and/or prophylaxis of type 1 or type 2 diabetes mellitus or complications associated with type 1 or type 2 diabetes mellitus include an insulin, e.g., human insulin, or a human insulin analogue or derivative, a glucagon-like peptide (GLP-1), GLP-1 analogues or GLP-1 receptor agonists, or an analogue or derivative thereof, a dipeptidyl peptidase-4 (DPP4) inhibitor, or a pharmaceutically acceptable salt or solvate thereof, or any mixture thereof. As used herein, the terms "analogue" and "derivative" refers to a polypeptide which has a molecular structure which formally can be derived from the structure of a naturally occurring peptide, for example that of human insulin, by deleting and/or exchanging at least one amino acid residue occurring in the naturally occurring peptide and/or by adding at least one amino acid residue. The added and/or exchanged amino acid residue can either be codable amino acid residues or other naturally occurring residues or purely synthetic amino acid residues. Insulin analogues are also referred to as "insulin receptor ligands". In particular, the term "derivative" refers to a polypeptide which has a molecular structure which formally can be derived from the structure of a naturally occurring peptide, for example that of human insulin, in which one or more organic substituent (e.g. a fatty acid) is bound to one or more of the amino acids. Optionally, one or more amino acids occurring in the naturally occurring peptide may have been deleted and/or replaced by other amino acids, including non-codeable amino acids, or amino acids, including non-codeable, have been added to the naturally occurring peptide.

Examples of insulin analogues are Gly(A21), Arg(B31), Arg(B32) human insulin (insulin glargine); Lys(B3), Glu(B29) human insulin (insulin glulisine); Lys(B28), Pro(B29) human insulin (insulin lispro); Asp(B28) human insulin (insulin aspart); human insulin, wherein proline in position B28 is replaced by Asp, Lys, Leu, Val or Ala and wherein in position B29 Lys may be replaced by Pro; Ala(B26) human insulin; Des(B28-B30) human insulin; Des(B27) human insulin and Des(B30) human insulin.

65 Examples of insulin derivatives are, for example, B29-N-myristoyl-des(B30) human insulin, Lys(B29) (N-tetradecanoyl)-des(B30) human insulin (insulin detemir,

Levemir®); B29-N-palmitoyl-des(B30) human insulin; B29-N-myristoyl human insulin; B29-N-palmitoyl human insulin; B28-N-myristoyl LysB28ProB29 human insulin; B28-N-palmitoyl-LysB28ProB29 human insulin; B30-N-myristoyl-ThrB29LysB30 human insulin; B30-N-palmitoyl-ThrB29LysB30 human insulin; B29-N-(N-palmitoyl-gamma-glutamyl)-des(B30) human insulin, B29-N-omega-carboxypentadecanoyl-gamma-L-glutamyl-des(B30) human insulin (insulin degludec, Tresiba®); B29-N-(N-lithocholy-l-gamma-glutamyl)-des(B30) human insulin; B29-N-(omega-carboxyheptadecanoyl)-des(B30) human insulin and B29-N-(omega-carboxyheptadecanoyl) human insulin.

Examples of GLP-1, GLP-1 analogues and GLP-1 receptor agonists are, for example, Lixisenatide (Lyxumia®), Exenatide (Exendin-4, Byetta®, Bydureon®, a 39 amino acid peptide which is produced by the salivary glands of the Gila monster), Liraglutide (Victoza®), Semaglutide, Taspo-glutide, Albiglutide (Syncria®), Dulaglutide (Trulicity®), rExendin-4, CJC-1134-PC, PB-1023, TTP-054, Lan-glenatide/HM-11260C (Efpeglenatide), HM-15211, CM-3, GLP-1 Eligen, ORMD-0901, NN-9423, NN-9709, NN-9924, NN-9926, NN-9927, Nodezen, Viador-GLP-1, CVX-096, ZYOG-1, ZYD-1, GSK-2374697, DA-3091, MAR-701, MAR709, ZP-2929, ZP-3022, ZP-DI-70, TT-401 (Pegapamodtide), BHM-034, MOD-6030, CAM-2036, DA-15864, ARI-2651, ARI-2255, Tirzepatide (LY3298176), Bamadutide (SAR425899), Exenatide-XTEN and Gluca-gon-Xten.

An example of an oligonucleotide is, for example: mipomersen sodium (Kynamro®), a cholesterol-reducing antisense therapeutic for the treatment of familial hypercholesterolemia or RG012 for the treatment of Alport syndrom.

Examples of DPP4 inhibitors are Linagliptin, Vildagliptin, Sitagliptin, Denagliptin, Saxagliptin, Berberine.

Examples of hormones include hypophysis hormones or hypothalamus hormones or regulatory active peptides and their antagonists, such as Gonadotropine (Follitropin, Lutropin, Choriongonadotropin, Menotropin), Somatropine (Somatropin), Desmopressin, Terlipressin, Gonadorelin, Triptorelin, Leuprorelin, Buserelin, Nafarelin, and Goserelin. Examples of polysaccharides include a glucosaminoglycane, a hyaluronic acid, a heparin, a low molecular weight heparin or an ultra-low molecular weight heparin or a derivative thereof, or a sulphated polysaccharide, e.g. a poly-sulphated form of the above-mentioned polysaccharides, and/or a pharmaceutically acceptable salt thereof. An example of a pharmaceutically acceptable salt of a poly-sulphated low molecular weight heparin is enoxaparin sodium. An example of a hyaluronic acid derivative is Hylan G-F 20 (Synvisc®), a sodium hyaluronate.

The term "antibody", as used herein, refers to an immunoglobulin molecule or an antigen-binding portion thereof. Examples of antigen-binding portions of immunoglobulin molecules include F(ab) and F(ab')2 fragments, which retain the ability to bind antigen. The antibody can be polyclonal, monoclonal, recombinant, chimeric, de-immunized or humanized, fully human, non-human, (e.g., murine), or single chain antibody. In some embodiments, the antibody has effector function and can fix complement. In some embodiments, the antibody has reduced or no ability to bind an Fc receptor. For example, the antibody can be an isotype or subtype, an antibody fragment or mutant, which does not support binding to an Fc receptor, e.g., it has a mutagenized or deleted Fc receptor binding region. The term antibody also includes an antigen-binding molecule based on tetravalent bispecific tandem immunoglobulins (TBTI) and/or a

dual variable region antibody-like binding protein having cross-over binding region orientation (CODV).

The terms "fragment" or "antibody fragment" refer to a polypeptide derived from an antibody polypeptide molecule (e.g., an antibody heavy and/or light chain polypeptide) that does not comprise a full-length antibody polypeptide, but that still comprises at least a portion of a full-length antibody polypeptide that is capable of binding to an antigen. Antibody fragments can comprise a cleaved portion of a full length antibody polypeptide, although the term is not limited to such cleaved fragments. Antibody fragments that are useful in the present disclosure include, for example, Fab fragments, F(ab')2 fragments, scFv (single-chain Fv) fragments, linear antibodies, monospecific or multispecific antibody fragments such as bispecific, trispecific, tetraspecific and multispecific antibodies (e.g., diabodies, triabodies, tetrabodies), monovalent or multivalent antibody fragments such as bivalent, trivalent, tetravalent and multivalent antibodies, minibodies, chelating recombinant antibodies, tri-bodies or bibodies, intrabodies, small modular immunopharmaceuticals (SMIP), binding-domain immunoglobulin fusion proteins, camelized antibodies, and immunoglobulin single variable domains. Additional examples of antigen-binding antibody fragments are known in the art.

The term "immunoglobulin single variable domain" (ISV), interchangeably used with "single variable domain", defines immunoglobulin molecules wherein the antigen binding site is present on, and formed by, a single immunoglobulin domain. As such, immunoglobulin single variable domains are capable of specifically binding to an epitope of the antigen without pairing with an additional immunoglobulin variable domain. The binding site of an immunoglobulin single variable domain is formed by a single heavy chain variable domain (VH domain or VHH domain) or a single light chain variable domain (VL domain). Hence, the antigen binding site of an immunoglobulin single variable domain is formed by no more than three CDRs.

An immunoglobulin single variable domain (ISV) can be a heavy chain ISV, such as a VH (derived from a conventional four-chain antibody), or VHH (derived from a heavy-chain antibody), including a camelized VH or humanized VHH. For example, the immunoglobulin single variable domain may be a (single) domain antibody, a "dAb" or dAb or a Nanobody® ISV (such as a VHH, including a humanized VHH or camelized VH) or a suitable fragment thereof. [Note: Nanobody® is a registered trademark of Ablynx N.V.]; other single variable domains, or any suitable fragment of any one thereof.

"VHH domains", also known as VHHs, VHH antibody fragments, and VHH antibodies, have originally been described as the antigen binding immunoglobulin variable domain of "heavy chain antibodies" (i.e., of "antibodies devoid of light chains"; Hamers-Casterman et al. 1993 (Nature 363: 446-448). The term "VHH domain" has been chosen in order to distinguish these variable domains from the heavy chain variable domains that are present in conventional 4-chain antibodies (which are referred to herein as "VH domains") and from the light chain variable domains that are present in conventional 4-chain antibodies (which are referred to herein as "VL domains"). For a further description of VHH's, reference is made to the review article by Muyldermans 2001 (Reviews in Molecular Biotechnology 74: 277-302).

For the term "dAb's" and "domain antibody", reference is for example made to Ward et al. 1989 (Nature 341: 544), to Holt et al. 2003 (Trends Biotechnol. 21: 484); as well as to

WO 2004/068820, WO 2006/030220, WO 2006/003388. It should also be noted that, although less preferred in the context of the present disclosure because they are not of mammalian origin, single variable domains can be derived from certain species of shark (for example, the so-called "IgNAR domains", see for example WO 2005/18629).

The terms "Complementarity-determining region" or "CDR" refer to short polypeptide sequences within the variable region of both heavy and light chain polypeptides that are primarily responsible for mediating specific antigen recognition. The term "framework region" refers to amino acid sequences within the variable region of both heavy and light chain polypeptides that are not CDR sequences, and are primarily responsible for maintaining correct positioning of the CDR sequences to permit antigen binding. Although the framework regions themselves typically do not directly participate in antigen binding, as is known in the art, certain residues within the framework regions of certain antibodies can directly participate in antigen binding or can affect the ability of one or more amino acids in CDRs to interact with antigen.

Examples of antibodies are anti PCSK-9 mAb (e.g., Alirocumab), anti IL-6 mAb (e.g., Sarilumab), and anti IL-4 mAb (e.g., Dupilumab).

Pharmaceutically acceptable salts of any API described herein are also contemplated for use in a drug or medicament in a drug delivery device. Pharmaceutically acceptable salts are for example acid addition salts and basic salts.

Those of skill in the art will understand that modifications (additions and/or removals) of various components of the APIs, formulations, apparatuses, methods, systems and embodiments described herein may be made without departing from the full scope and spirit of the present disclosure, which encompass such modifications and any and all equivalents thereof.

An example drug delivery device may involve a needle-based injection system as described in Table 1 of section 5.2 of ISO 11608-1:2014(E). As described in ISO 11608-1:2014 (E), needle-based injection systems may be broadly distinguished into multi-dose container systems and single-dose (with partial or full evacuation) container systems. The container may be a replaceable container or an integrated non-replaceable container.

As further described in ISO 11608-1:2014(E), a multi-dose container system may involve a needle-based injection device with a replaceable container. In such a system, each container holds multiple doses, the size of which may be fixed or variable (pre-set by the user). Another multi-dose container system may involve a needle-based injection device with an integrated non-replaceable container. In such a system, each container holds multiple doses, the size of which may be fixed or variable (pre-set by the user).

As further described in ISO 11608-1:2014(E), a single-dose container system may involve a needle-based injection device with a replaceable container. In one example for such a system, each container holds a single dose, whereby the entire deliverable volume is expelled (full evacuation). In a further example, each container holds a single dose, whereby a portion of the deliverable volume is expelled (partial evacuation). As also described in ISO 11608-1:2014 (E), a single-dose container system may involve a needle-based injection device with an integrated non-replaceable container. In one example for such a system, each container holds a single dose, whereby the entire deliverable volume is expelled (full evacuation). In a further example, each container holds a single dose, whereby a portion of the deliverable volume is expelled (partial evacuation).

An example of a compound to be administered with the drug delivery device disclosed herein is a compound with the INN tirzepatide, as referenced in claim 1 of U.S. Pat. No. 9,474,780.

5 An example of a pharmaceutical composition to be administered with the drug delivery device disclosed herein is a pharmaceutical composition as referenced in U.S. Pat. No. 11,357,820.

10 An example of a pharmaceutical composition to be administered with the drug delivery device disclosed herein includes a 0.5 mL solution of 2.5 mg, 5 mg, 7.5 mg, 10 mg, 12.5 mg, or 15 mg of tirzepatide and the following excipients sodium chloride (4.1 mg), sodium phosphate dibasic heptahydrate (0.7 mg), and water for injection. Hydrochloric acid solution and/or sodium hydroxide solution may be added to adjust the pH.

15 An example starting dosage tirzepatide may be 2.5 mg injected subcutaneously once weekly. After four weeks, the tirzepatide dosage may be increased to 5 mg injected subcutaneously once weekly. The dosage may be further increased in 2.5 mg increments after at least four weeks on the current dose. In an example, the maximum dosage of tirzepatide may be 15 mg injected subcutaneously once weekly. If a dose is missed, patients may be instructed to 20 administer tirzepatide as soon as possible within four days (96 hours) after the missed dose. If more than four days have passed, patients may skip the missed dose and administer the next dose on the regularly scheduled day. In each case, patients may then resume their regular once weekly dosing schedule. The day of weekly administration may be changed, if necessary. The time between two doses may be 25 at least three days (72 hours).

20 Tirzepatide dosages may include 2.5 mg/0.5 mL, 5 mg/0.5 mL, 7.5 mg/0.5 mL, 10 mg/0.5 mL, 12.5 mg/0.5 mL, and 15 mg/0.5 mL. Tirzepatide may be stored in a refrigerator at 2° C. to 8° C. (36° F. to 46° F.). A single-dose pen or single-dose vial may be stored unrefrigerated at temperatures not to exceed 30° C. (86° F.) for up to 21 days. Tirzepatide may be stored in a carton.

The invention claimed is:

1. A medicament delivery device for injecting medicament, the medicament delivery device comprising:
 a body having a proximal end and a distal end;
 a needle;
 an actuation member movable relative to the body, wherein the actuation member is movable from a first position to a second position, wherein the second position is proximal of the first position, and wherein the actuation member is movable from the second position to a dispensing position for dispensing the medicament via the needle; and
 a cap removably attached to the medicament delivery device, wherein the cap comprises a proximally-extending portion configured to prevent movement of the actuation member from the first position to the second position when the cap is attached to the medicament delivery device;
 wherein the actuation member comprises an axially-extending component which engages the proximally-extending portion when the cap is attached to the medicament delivery device for preventing movement of the actuation member from the first position to the second position;
 wherein one of the proximally-extending portion and the axially-extending component comprises a protrusion and the other of the proximally-extending portion and the axially-extending component comprises a recess, wherein the protrusion is received in the recess when the cap is attached to the medicament delivery device to prevent movement of the actuation member from the first position to the second position.
2. The medicament delivery device of claim 1, wherein the medicament delivery device comprises a bias configured to bias the actuation member from the first position to the second position.

3. The medicament delivery device of claim 1, wherein the actuation member is configured such that when the actuation member is in the first position, the proximal end of the actuation member is located distally from the proximal end of the medicament delivery device.
4. The medicament delivery device of claim 1, wherein the actuation member is configured such that when the actuation member is in the second position, the actuation member protrudes from a part of the medicament delivery device.
5. The medicament delivery device of claim 1, wherein at least one of the recess and the protrusion comprises a ramped surface for allowing the protrusion to disengage the recess when the cap is removed from the medicament delivery device.
6. The medicament delivery device of claim 1, wherein the proximally-extending portion is flexible, and wherein the proximally-extending portion is configured to flex when the cap moves distally and the protrusion disengages the recess.
7. The medicament delivery device of claim 1, wherein the medicament delivery device comprises a lock ring configured to rotate the actuation member relative to the body from the second position to a third position, and wherein the actuation member is distally movable from the third position to the dispensing position.
8. The medicament delivery device of claim 1, wherein the cap is configured such that when the cap is attached to the body, the cap covers the distal end of the body for preventing access to the needle.
9. The medicament delivery device of claim 1, wherein the cap is removably attached to the body.
10. The medicament delivery device of claim 1, further comprising a dispensing mechanism configured to dispense medicament via the needle, and wherein the actuation member is configured to release the dispensing mechanism when the actuation member is in the dispensing position.
11. The medicament delivery device of claim 1, wherein the actuation member is configured to be rotated relative to the body.
12. The medicament delivery device of claim 1, wherein the actuation member comprises one of a slot and a protrusion, and wherein a second component of the medicament delivery device comprises the other of the slot and the protrusion, wherein the protrusion is located in the slot and wherein the slot has a circumferentially-extending portion configured to rotate the actuation member relative to the second component when the protrusion moves in the circumferentially-extending portion and the actuation member moves from the first position to the second position.
13. The medicament delivery device of claim 12, wherein the second component is the body.
14. The medicament delivery device of claim 1, wherein the actuation member comprises a button configured to be pressed to move the actuation member to the dispensing position.
15. The medicament delivery device of claim 1, further comprising a container containing the medicament.
